UNITED STATES PATENT OFFICE.

CHARLES E. SKINNER, OF WILKINSBURG, PENNSYLVANIA, ASSIGNOR TO WESTINGHOUSE ELECTRIC AND MANUFACTURING COMPANY, A CORPORATION OF PENNSYLVANIA.

INSULATING FABRIC.

1,161,989.

Specification of Letters Patent. Patented Nov. 30, 1915.

Original application filed October 7, 1908, Serial No. 456,609. Divided and this application filed May 16, 1908. Serial No. 561,746.

To all whom it may concern:

Be it known that I, CHARLES E. SKINNER, a citizen of the United States, and a resident of Wilkinsburg, in the county of Allegheny and State of Pennsylvania, have invented a new and useful Improvement in Insulating Fabrics, of which the following is a specification, this application being a division of my application, Serial No. 456,609, filed October 7, 1908.

My invention relates to insulating fabrics for electrical apparatus and it has for its object to provide a fire-proof fabric which shall be adapted for use at relatively high temperature.

Field coils for dynamo-electric machines have heretofore been constructed by winding copper strap or ribbon into a rectangular helix, and, since the voltage between turns in coils of this character is relatively low, strips of insulating material have usually been inserted between the turns of the helix in preference to wrapping the conductor with insulating tape or completely covering it by other means, in order to improve the ventilation of the winding.

According to my present invention, I provide a fabric composed of metal foil or very thin metal ribbon which has been so treated as to produce a hard film or coating of insulation on its surface. Since foil of approximately one-thousandth of an inch in thickness may be employed, the space occupied by the insulation is relatively small while, at the same time, the coil, or other electrical conductor with which it is used, is rendered fire-proof and capable of operation at high temperatures. The coated metal foil (preferably aluminum) may be used in combination with sheet mica, the foil serving to hold the mica sheets or flakes in position, thereby avoiding the necessity for paper or other carbonizable fabric, such as is usually employed.

Figure 1 of the accompanying drawings, is a sectional view, on a large scale, of a sheet or strip of metal foil which has been treated to produce the insulating fabric of my invention. Fig. 2 is a similar view of an insulating fabric which is built up of several layers of the kind shown in Fig. 1 and separated by sheet mica or other similar insulating material. Fig. 3 is a perspective view of an insulating ribbon or strip which is similar in construction to the fabric of Fig.

2, the parts or layers being separated for clearness of illustration.

Referring to the drawings, 1 represents a section of aluminum foil having insulating coatings 2 and 3 which are produced by treating the foil electrolytically, or otherwise.

Referring to Figs. 2 and 3, the fabric here shown in section, is composed of three layers 4, 5 and 6 of coated aluminum foil separated by layers 7 and 8 of mica or other similar insulating material. By using the mica flakes, in combination with the aluminum foil, the insulating fabric is adapted to insulate for relatively high voltages while, at the same time, no combustible material is introduced.

I prefer to employ strips of aluminum foil of substantially one-thousandth of an inch in thickness in order that a minimum amount of space may be occupied by the insulation when used in connection with coils and other current-conducting parts.

An especially good insulating film may be obtained by passing the strip of aluminum through a bath of ammonium borate, or some other suitable liquid, and, at the same time, passing electric current through the conductor and the bath. By this means, an aluminum oxid film, which is relatively hard and is not readily destroyed by heat, is produced. Either one or both of the surfaces of the metal foil may be covered with the insulating film.

My invention is not limited to use with any particular form or type of electric apparatus but is capable of application for all insulating purposes where sheet insulating material can be employed.

I claim as my invention:

1. A fire-proof material for insulating electric conductors consisting of metal foil having a heat-resisting coating of hard insulating material upon its surface.

2. A fire-proof material for insulating electric conductors consisting of aluminum foil having a heat-resisting coating of hard insulating material formed upon its surface.

3. A fire-proof insulation comprising alternate layers of metal foil having insulating coatings on their surfaces and other heat-resisting insulating material.

4. A fire-proof insulating material comprising alternate layers of aluminum foil having oxid insulating coatings on their sur-

faces and mica flakes, the mica flakes held being in position by the foil.

5. A fireproof insulating material comprising non-combustible sheet material coated with non-combustible insulating material.

6. A fireproof insulating material comprising oxidized aluminum foil.

In testimony whereof, I have hereunto subscribed my name this 3rd day of May, 1910.

CHARLES E. SKINNER.

B. B. HINES.

Corrections in Letters Patent No. 1,161,989.

It is hereby certified that in Letters Patent No. 1,161,989, granted November 30, 1915, upon the application of Charles E. Skinner, of Wilkinsburg, Pennsylvania, for an improvement in "Insulating Fabrics," errors appear in the printed specification requiring correction as follows: Page 1, line 15, for the word "temperature" read *temperatures*; page 2, lines 1-2, for the words "held being" read *being held*; and that the said Letters Patent should be read with these corrections therein that the same may conform to the record of the case in the Patent Office.

Signed and sealed this 18th day of January, A. D., 1916.

[SEAL.]

J. T. NEWTON,

Acting Commissioner of Patents.

Cl. 173—320.
